(No Model.)

J. T. HAMBAY.

TEST LOCK FOR SWITCH AND SIGNAL APPARATUS.

No. 429,193.

Patented June 3, 1890.

FIG.1.

FIG.2.

INVENTOR,
James T. Hambay
by George H. Christy
Atty.

UNITED STATES PATENT OFFICE.

JAMES T. HAMBAY, OF WILKINSBURG, ASSIGNOR TO THE UNION SWITCH AND SIGNAL COMPANY, OF PITTSBURG, PENNSYLVANIA.

TEST-LOCK FOR SWITCH AND SIGNAL APPARATUS.

SPECIFICATION forming part of Letters Patent No. 429,193, dated June 3, 1890.

Application filed February 21, 1889. Serial No. 300,705. (No model.)

To all whom it may concern:

Be it known that I, JAMES T. HAMBAY, a citizen of the United States, residing at Wilkinsburg, in the county of Allegheny and State of Pennsylvania, have invented or discovered certain new and useful Improvements in Test-Locks for Switch and Signal Apparatus, of which improvements the following is a specification.

10 The invention described herein relates to certain improvements in switch and signal apparatus, and has for its object a construction and arrangement of locking devices whereby the signal-man is enabled after every 15 switch movement in a yard or portion thereof to ascertain whether the switches have been fully shifted and in such position as will allow the movements of trains thereover, and simultaneous with such test to lock all the 20 switches included in the test movement.

In general terms, the invention consists in the construction and arrangement of mechanical devices or elements, all as more fully herein described and claimed.

25 In the accompanying drawings, forming a part of this specification, Figure 1 is a plan view of a portion of a yard having my invention applied thereto, and Fig. 2 is a perspective view of the test-lock.

30 For purposes of illustration and description I have shown my invention as applied to the switches *a*, *b*, *c*, *d*, and *e* of the main lines of track A and B, the switches *a*, *b*, *c*, and *d* being cross-over switches. The movements of these several switches are effected 35 by suitable mechanisms 1^a 1^b 1^c , &c., preferably of the construction shown and described in Letters Patent No. 399,888, dated March 19, 1889. These switch-shifting mechanisms are 40 operated by levers of a suitable interlocking-machine located in a tower, as indicated at D. To the movable switch-rails are connected locking-bars 2, which, as at switches *a* and *d*, may be continuations of the locking-bar 3, forming a part of the switch-shifting mechanisms 45 1^a and 1^d , or, as at switches *b*, *c*, and *e*, may project in the opposite direction from the locking-bar 3, but are preferably connected at the same point to the movable 50 switch-rails. These locking-bars 2 pass at

their outer ends through slots in a guide-plate 4, secured to cross-ties or to any other suitable support, and when shifted by the switch-rails move transversely to the lines of movement of the locking-pins 5. These locking-pins 55 are mounted in bearings 6, preferably formed on the sides of the plates 4, as shown in Fig. 2, and are connected to a rod or pipe 7, extending from a lever in the tower D. The locking-bars 2 are provided with suitable 60 openings for the reception of the pins 5, said openings being so located that one or the other of them will be in line with the locking-pins when the switches have been fully 65 shifted to one or the other of their positions and locked by the mechanisms 1^a 1^b , &c. The lever to which the rod 7 is connected is so interlocked by any of the well-known systems of interlocking with the levers employed for operating the signals shown at S as to require 70 said lever to be so shifted as to cause pins 5 to engage the locking-bars 2 before any of the signal-levers can be shifted to clear the signals; but said lever is not locked by the movements of the signal-levers, as otherwise 75 the clearing of any of the signals for one combination or arrangement of track would lock up the whole yard.

In operating a switch and signal apparatus embodying my invention it is necessary before any switch movement can be effected that the lever connected to the rod 7 be shifted so as to withdraw the pins 5 from engagement with the locking-bars 2. Any desired switch movement can then be effected through the 80 medium of the mechanisms 1^a 1^b , &c., such switch movements being accompanied by the orderly movements of the locking mechanisms and detector-rails forming part of the mechanisms 1^a , &c., as described in the 85 Letters Patent hereinbefore referred to; but as the locking-pin lever, in withdrawing the pins 5 from the locking-bar, locked the signals at "danger," it is necessary to so shift said lever as to cause the pins 5 to again engage the locking-bars 2, thereby testing the 90 positions of the switches before the signal or signals can be again cleared. It will be understood that the levers for operating the 95 switch mechanisms and the levers for shifting 100

the signals are interlocked, as usual, and hence it is necessary not only that the switch mechanisms 1 1^a, &c., be operated to properly shift the switches, but also that the locking-pin lever be shifted to test the switch movements before a signal can be cleared. As the pins 5 do not have any connection to the switch-locks proper or the detector-rails, said pins may be shifted at any time, and these pins 10 and their operating mechanism are independent of the switch and signal apparatus, except that a test movement of the pins is necessary before a signal at danger can be cleared. It will be observed that apparatus as described 15 is more in the nature of a lock-test for determining whether the switch mechanism has properly performed its function of shifting and locking the switch. This mechanism is not designed to replace the switch 20 shifting and locking mechanism, but is supplemental thereto.

It is not necessary to provide a lock for every switch in a yard, but it is necessary that the proper position of the switch should 25 be insured before the signal is cleared; hence the lever for operating the lock-test is so interlocked in the machine as to require a test movement thereof before the signal can be cleared, but interlocking mechanism is so 30 constructed that the clearing of the signal will not lock the test-lever.

I claim herein as my invention—

1. The combination of a railroad-yard consisting of a series of two or more switches, each 35 provided with mechanism for shifting and locking the rails thereof, and a corresponding series of lock-tests for insuring the proper adjustment of the switches in either of the positions thereof, all of said lock-tests being 40 connected to and operated simultaneously by a single lever, substantially as set forth.

2. The combination of a railroad-yard consisting of a series of two or more switches, each provided with a locking-bar and with mechanism for shifting and locking the rails 45 thereof, and a series of two or more pins adapted to engage said bars in either of the positions of the switch-rails, all of said pins being connected to and operated by a single lever, substantially as set forth. 50

3. The combination of a railroad-yard consisting of a series of two or more switches, each provided with mechanism for shifting and locking the rails thereof, a corresponding series of lock-tests for insuring the proper 55 adjustment of the switches in either of the positions thereof, all of said lock-tests being connected to and operated by a single lever, and signal-operating levers controlled by the lever for operating the lock-tests, substantially 60 as set forth.

4. The combination of a railroad-yard consisting of a series of two or more switches, a corresponding series of lock-tests for insuring the proper adjustment of the switches in 65 either of the positions thereof, all of said lock-tests being connected to and operated simultaneously by a single lever, signals controlling the movements of trains in the yard, the levers for operating said signals being so 70 interlocked with the lever operating the test-locks as to require a testing movement of the latter before the signals can be cleared, and the clearing of the signals will not lock the test-lever, substantially as set forth. 75

In testimony whereof I have hereunto set my hand.

JAMES T. HAMBAY.
